(57) **CLAIM**

We claim the ornamental design for a muddler stick, as shown and described.

DESCRIPTION

FIG. 1 is a perspective view of the muddler stick, showing our new, original and ornamental design;

FIG. 2 is a side view thereof;

FIG. 3 is a second side view thereof;

FIG. 4 is a top view thereof; and,

FIG. 5 is a bottom view thereof.

The broken lines in the figures are for illustrative purposes only and form no part of the claimed design.
